CLAIM

The ornamental design for a portable processing terminal, as shown and described.

DESCRIPTION

FIG. 1 is a front perspective view of the portable processing terminal with broken lines illustrating an inserted battery; FIG. 2 is a front perspective view thereof, without broken lines;

FIG. 3 is a front elevational view of FIG. 2;

FIG. 4 is a rear elevational view of FIG. 2;

FIG. 5 is a right side elevational view of FIG. 2 with broken lines illustrating contact aspects;

FIG. 6 is a right side elevational view of FIG. 2 without broken lines;

FIG. 7 is a left side elevational view of FIG. 2;

FIG. 8 is a top view of FIG. 1;

FIG. 9 is a top view of FIG. 2; and,

FIG. 10 is a bottom view of FIG. 1.

Any elements shown in dash-dot lines form no part of the claimed invention in this application, and are instead included to show environmental aspects of the claimed invention.
